UNITED STATES PATENT OFFICE.

CARL GABRIELSON, OF SPRINGFIELD, MASSACHUSETTS, ASSIGNOR TO UNION TYPEWRITER COMPANY, OF JERSEY CITY, NEW JERSEY, A CORPORATION OF NEW JERSEY.

TYPE-WRITING MACHINE.

SPECIFICATION forming part of Letters Patent No. 716,701, dated December 23, 1902.

Application filed October 30, 1901. Serial No. 80,518. (No model.)

To all whom it may concern:

Be it known that I, CARL GABRIELSON, a citizen of the United States, and a resident of Springfield, in the county of Hampden and State of Massachusetts, have invented certain new and useful Improvements in Type-Writing Machines, of which the following is a specification.

The object of my invention is to provide simple and efficient means for effecting a varying lateral movement of the inking-ribbon, as well as a longitudinal movement thereof, so as to use the ribbon both widthwise and lengthwise.

To this end my invention consists in the novel features of construction and arrangements and combinations of parts hereinafter described and claimed.

In the accompanying drawings, wherein like reference characters indicate corresponding parts in the various views, Figure 1 is a central vertical longitudinal sectional view from front to rear of a type-writing machine embodying my invention. Fig. 2 is a horizontal sectional view of the same, taken immediately below the top plate. Fig. 3 is a transverse vertical sectional view of the machine, taken at the line X in Fig. 1 and looking toward the rear of the machine, but omitting some of the parts shown in Fig. 1 for the sake of clearness. Fig. 4 is a detail perspective view of the movable ribbon-guide. Fig. 5 is a detail perspective view of one of the yokes which form a pair of parallel links for moving the ribbon-guide. Fig. 6 is a fragmentary perspective view of portions of three type-bars and their projections. Fig. 7 is a fragmentary perspective view of a modification.

In the various views parts are omitted and broken away to better illustrate other parts of the construction.

1 is the general framework, 2 the top plate, and 3 the key-levers, which are pivoted at 4 and provided with finger-keys or buttons 5. A sublever 6 is pivoted to each key-lever 3 at 7 and is slotted at 8 in order to embrace the fixed fulcrum-rod 9. The upper end of each of these levers 6 is pivoted to a for-

wardly-extending link 10, as indicated at 11, 50 the forward end of each link being in turn pivoted to a type bar or carrier 12, as indicated at 13. These type-bars are pivoted upon a curved rod 14, supported in a segment 15, which is slotted radially to accommodate the hub ends of the type-bars. Extending beneath the various key-levers 3 is a universal bar 16, which is connected to-links 17, that in turn are connected to arms 18, which are united to a bar 19, that in turn is 60 secured to a crank-arm 20, pivoted at 21 and supporting the feed-dog carrier 22, having the usual feed-dogs 23, that coöperate with a feed-wheel 24, that is connected to a shaft which turns in a bearing 25, that is secured to the 65 top plate of the machine, as indicated at 26. The opposite end of the shaft, to which the feed-wheel 24 is operatively connected, has secured thereto a feed-pinion 27, which coöperates with the feed-rack 28, that is carried by 70 a carriage 29, in which a platen 30 is mounted. The carriage 29 is connected to a spring-drum 31 by means of a band 32, so as to move the carriage in the direction of its feed. The revolving spring-drum 31 is operatively connected to a bevel-pinion 33, which meshes with a coöoperating bevel-pinion 34, carried upon a longitudinally-extending shaft 35, which is provided with bevel-pinnions 36, 75 which are adapted to alternately mesh with coöoperating bevel-pinnions 37, each of which is connected to a shaft 38, that carries at its opposite end a driving-pinion 39, that coöperates with a pinion 40 upon the shaft of one of the ribbon-spools 41. These ribbon-spools 80 41 are mounted upon opposite sides of the machine, and the ribbon 42 in passing from spool to spool extends through apertures 43 in the bifurcated movable ribbon-guide 44. The movable ribbon-guide 44 is provided 85 with bent and rearwardly-deflected ears 45, which are perforated, as indicated at 46, for pivotal connection with parallel links 47, the said pivotal connection being indicated at 48. The parallel links 47 are preferably 90 formed of two yokes of the general construction represented in Fig. 5 of the drawings. These yokes may be pivoted at 50 to an arm 95

- 49, depending from the top plate 2. One of the yokes is provided with an upwardly-extending arm 51, to which a rod 52 is pivoted at 53. The opposite end of this rod 52 is secured to a segmental bar or plate 54, which is provided near each end with a rod 55, that is pivoted at 57 to an arm 56, whose lower end is pivoted at 59 to a stud 58, depending from the top plate.
- 10 Each of the type-bars 12 is provided with a lug or projection 60, preferably formed integral with the stock of the type-bar. These lugs or projections 60 project to different extents from the upper or inner edges of the different type-bars, as indicated in Figs. 1, 3, and 6 of the drawings, and they are each adapted to contact with the plate 54 when the type-bar has nearly completed its printing stroke and to move the plate 54 rearwardly or in the direction of the arrow in Fig. 1 of the drawings. The movement thus imparted to the plate 54 will force the rod 52 rearwardly, thereby causing the lower frame 47 to be rocked on its pivots 50, thus elevating the movable ribbon-guide 44 to bring the ribbon into the path of the type on the type-bar before it reaches the printing-point. The weights of the ribbon-guide and the parts connected thereto are sufficient to restore the ribbon-guide to the normal position, (illustrated in Fig. 1,) thus conveying the ribbon-guide to the inoperative position to expose the last written character on the paper; but a returning-spring may be added, if desired.
- 35 It will be understood that the projections 60 on the different segmentally-arranged type-bars will force the plate 54 rearwardly to different extents by reason of the fact that the projections on the different bars are of different lengths, and hence different type-bars will cause the ribbon to be lifted or moved transversely of its length different distances or to varying extents, and thus insure the use of the ribbon crosswise as well as longitudinally. It will likewise be understood that while the lateral movements of the ribbon may be varied by the operations of the different type-bars the relationship of the parts is such that the ribbon will at all times be raised into the path of the type on a type-bar and will be dropped to a position where the writing is exposed as the type-bar returns to normal position.
- In a machine using a narrow ribbon it may not be necessary to provide more than three or four series of projections 60 of different lengths or heights, and these sets or series may be variously disposed throughout the type-bar system. I have shown at Fig. 3 a set of three projections arranged in step-like order; but the number in a set may be less or greater than three so long as the projections vary and are able to cause the ribbon to move widthwise different degrees.
- 65 The inking-ribbon is moved longitudinally or from one spool to the other after the type-bar has moved the ribbon transversely and

made its impression upon the paper upon the platen by means of the gearing between the spring-drum and the ribbon-spool shaft, as shown and as is common in prior machines—that is to say, after the type impression and when the carriage moves one letter-space to the left the spring-drum turns the shaft 35 and the counter-shaft 38 and its associated ribbon-spool 41, which for the time being are connected with said shaft 35, and the ribbon is thus wound one step or for a small portion upon said spool. When this spool has been filled, the ribbon-winding may be reversed by shifting the shaft 35 endwise and causing it to be connected with the opposite counter-shaft 38 and its associated spool.

I have illustrated my invention in its application to a "front-strike" type-writing machine, and while the invention considered from certain aspects is particularly adapted for so-called "visible-writing" machines, of which the front-strike machine is one variety, the invention may be employed in other types of machines and various changes may be made in the construction to adapt the invention to such other machines.

Instead of providing projections 60 of different lengths upon the type-carriers the plate 54 may be provided with variously-projecting contact-surfaces 60^a, which coöperate with the type-bars at different periods of their movements to the printing-point, as indicated at Fig. 7.

I prefer to provide the plate 54 with a cushion or facing 54^a of leather, rubber, or the like to prevent undue noise when the type-bars strike and operate the plate 54.

In some cases the projections 60 may be omitted and the remainder of the mechanism be used simply for moving the inking-ribbon from the normal position, which exposes the last letter printed, to a position where it will be interposed between the type and the paper just before the type reaches printing position.

Having described my invention, what I claim as new, and desire to secure by Letters Patent, is—

1. In a type-writing machine, the combination of type-carriers, means for actuating the type-carriers and means coöperating with the type-carriers for moving the ribbon varying extents in a lateral direction.

2. In a type-writing machine, the combination of a platen, type-carriers, means for actuating the type-carriers and means coöperating with the type-carriers for moving the ribbon varying extents into and out of the path of the types on the carriers as they are moved to the platen.

3. In a type-writing machine, the combination of a platen, type-carriers, means for actuating the type-carriers and means coöperating with the type-carriers for moving the ribbon transversely varying extents into the path of the type on the carriers as they are moved to the platen.

4. In a type-writing machine, the combina-

tion of a platen, type-carriers, means for moving the type-carriers, a movable ribbon-guide which is adapted to move the ribbon laterally into the path of the types on the type-carriers, 5 and mechanism between the ribbon-guide and type-carriers adapted to be moved by the type-carriers to move the ribbon to different extents by the different type-carriers.

5. In a type-writing machine, the combination of a platen, type-carriers, means for moving the type-carriers, a movable ribbon-guide which is adapted to move the ribbon laterally into the path of the type on the type-carriers, mechanism between the ribbon-guide and 15 type-carriers adapted to be moved by the type-carriers and varying projections between the type-carriers and the intermediate mechanism, for causing the ribbon to be moved different distances in a lateral direction when 20 different type-carriers are operated.

6. In a type-writing machine, the combination of a platen, type-carriers, means for moving the type-carriers, a movable ribbon-guide which is adapted to move the ribbon laterally into the path of the type on the type-carriers, 25 projections carried by said type-carriers, which projections are adapted to actuate the ribbon-guide and which vary on different carriers, so that an operation of the different 30 carriers will move the ribbon laterally to different extents.

7. In a type-writing machine, the combination of type-carriers and means for moving the ribbon laterally to different extents when 35 different carriers are operated.

8. In a type-writing machine, the combination of segmentally-arranged type-bars, a movable segmental bar or plate with which said type-bars coöperate to move it to different 40 extents when the different bars are operated, and a ribbon-guide operatively connected to said movable segmental bar or plate.

9. In a type-writing machine, the combination of segmentally-arranged type-bars, a movable ribbon-guide and a movable segmental bar or plate which is operatively connected to the ribbon-guide and with which said type-bars coöperate to move the ribbon varying 45 distances when the different bars are operated.

10. In a type-writing machine, the combination of segmentally-arranged type-bars, a movable ribbon-guide, a movable segmental 55 bar connected to said ribbon-guide to move it when the segmental bar is moved and projections on said type-bars which are adapted to contact with and move the segmental bar when the type-bars are moved to the printing 60 position, the said projections on the different type-bars being of different lengths so as to vary the movement imparted to the ribbon-guide when the different type-bars are operated.

65 11. In a type-writing machine, the combination of type-carriers, a movable ribbon-guide, parallel links to which said guide is

connected, a plate or bar which is adapted to be moved to different extents by the different type-carriers and intermediate connections 70 between the said movable bar or plate and the parallel links whereby the ribbon will be moved laterally to different extents by the operations of the different type-carriers.

12. In a type-writing machine, the combination of segmentally-arranged type-bars, a movable ribbon-guide which is adapted to be moved into the path of the type on the bars, parallel links to which said guide is connected, a segmental bar or plate which is adapted 80 to be moved to different extents by the different type-bars and intermediate connections between the said movable segmental bar or plate and the parallel links whereby the ribbon will be moved laterally to different 85 extents by the operations of the different type-carriers.

13. In a type-writing machine, the combination of ribbon-spools, means for feeding the ribbon from one spool to another, type-bars, 90 a ribbon-guide through which the ribbon passes in its movement from one spool to another, and means for moving the ribbon-guide to different extents to move the ribbon laterally to different extents, by the direct actions 95 of the type-bars.

14. In a type-writing machine, the combination of ribbon-spools, means for feeding the ribbon from one spool to another, type-bars, 100 a ribbon-guide through which the ribbon passes in its movement from one spool to another, projections on the type-bars and means coöperating with said projections for moving the ribbon-guide different distances by the operations of the different type-bars. 105

15. In a type-writing machine, the combination of ribbon-spools, means for feeding the ribbon from one spool to another, type-bars, a ribbon-guide through which the ribbon passes in its movement from one spool to another, a movable bar with which the type-bars contact at different points in their movement to the printing position and operative connections between said movable bar and ribbon-guide. 110 115

16. In a type-writing machine, the combination of type-carriers, a movable ribbon-guide and a part which is operatively connected to said guide and which is adapted to be moved varying distances by different type-bars. 120

17. In a type-writing machine, the combination of ribbon-spools, means for feeding the ribbon from one spool to another, type-bars, a ribbon-guide, projections of different 125 lengths on the different type-bars, a movable bar with which said projections contact in the movement of the type-bars to the printing position and intermediate connections between the movable bar and the ribbon-guide. 130

18. In a type-writing machine, the combination of ribbon-spools, means for feeding the ribbon from spool to spool, segmentally-arranged type-bars, a movable ribbon-guide

through which said ribbon passes in its movement from one spool to another, a segmental movable bar adapted to be moved varying distances by different type-bars and intermediate connections between said segmental bar and the ribbon-guide, whereby the ribbon will be moved laterally to different extents by the operations of different type-bars.

19. In a type-writing machine, the combination of a ribbon-carrier, type-carriers, and means variously affected by the type-carriers for moving the ribbon crosswise different distances.

20. In a type-writing machine, the combination of a ribbon-carrier, parallel links 47, 47, for operating and supporting said carrier, a plate or universal bar 54, supporting and guiding rods 55, 55, for said plate or bar, a rod 52 connecting said plate or bar with a crank-arm 51 connected to one of said links 47, and a set of type-carriers arranged to strike said plate or bar and through the said

rods, arms and links cause transverse movements of the ribbon.

21. In a type-writing machine, the combination of a ribbon-carrier, parallel pivoted links 47 pivotally attached to said carrier and one of said links having a crank-arm 51, a plate or universal bar 54, parallel rods 55 attached to said plate or bar, vibratory arms 56 to which said rods 55 are pivoted, a rod 52 also attached to said plate or bar and pivotally connected to said crank-arm 51, and a set of type-carriers adapted to strike said plate or bar and through the devices described cause transverse movements of the ribbon.

Signed at the borough of Manhattan, city of New York, in the county of New York and State of New York, this 25th day of October, A. D. 1901.

CARL GABRIELSON.
